UNITED STATES PATENT OFFICE

JAMES FREDERICK BUEL, OF WOBURN, MASSACHUSETTS

TURF ROLLER

Application filed January 8, 1931. Serial No. 507,366.

This invention relates to certain improvements in that type of devices which are designed to form small holes in lawns, or golf courses, so that water may have access more readily to the grass roots and the turf may be softened, and more particularly to devices for this purpose of the type in which a series of pointed fingers are mounted on a rotary holding means and are so arranged that, when the device is propelled over the ground, the fingers will be forced perpendicularly into the ground and withdrawn therefrom in the same position, so that the ground will not be torn up, or the holes which are formed unduly enlarged.

While various devices of this character have been produced, they have not, as far as I am aware, been extensively employed, for various reasons, some of which are believed to be due to the fact that they have not been constructed to permit convenient use on golf courses, where it is usually desirable to operate such devices on the putting greens only, thus making it necessary to transport the device from one green to another.

The objects of my invention are to provide a device of the character above referred to with means whereby it may be conveniently transported from place to place without performing the functions for which it is intended and, may be readily turned so that it may be propelled in different directions. Also to provide an improved construction whereby the spikes may be effectively combined with a roller, or series of rollers, and a device may be produced which will effectively perform both puncturing and rolling functions, and which is of durable construction, so that breakage may be reduced to a minimum, and repairs may be readily made in case breakage should occur.

I accomplish these objects by means of the construction hereinafter described, and as illustrated in the accompanying drawings in which:

Figs. 1 and 2 are side elevations of a device embodying the invention.

Fig. 3 is a sectional view, taken at the line $x-x$ of Fig. 2.

Fig. 4 is a side elevation of the device, partly broken away.

Figs. 5 and 6 are detail sectional views of a rim portion of one of the rolls, taken longitudinally and transversely thereof, respectively.

According to my invention, I provide a series of metal rolls, or wheels each of which comprises a hub 1, which is rotatably mounted on an axle 2, the ends of which are secured in a yoke 3, to which a handle 4 is connected. The diameter of the axle is preferably substantially less than the diameter of the bores of the hubs, so that the wheels may have some relative vertical movement. The wheels 1 are of identical construction, each comprising a heavy rim 5, mounted on the hub 1 by means of spokes, said rim having a cylindrical rolling face. The rim of each wheel is provided with a series of transversely disposed, regularly spaced holes, which extend in parallel relation to each other and to said face, from one side edge thereof to the other, approximately midway between said face and the inner periphery of the rim, and a series of shafts 6 are rotatably mounted therein. A series of pointed fingers, or spikes 7 are rigidly fixed in said shafts in right angular relation thereto, and in position to permit their pointed end portions to extend beyond the peripheral face of rim. In the arrangement shown in Fig. 6, a shaft 6 is extended beyond both edges of the rim and a spike 7 is set into and secured in each projecting end portion thereof close to the edges of the rim. A hole 8 is also formed thru the middle of the rim, and a third spike, as 7a, is passed thru said hole and thru the shaft, the shank portion of the spike being extended within the inner periphery of the rim.

As shown in Fig. 5, the outer portions of the holes 8 are enlarged at one side thereof and the inner portions are similarly enlarged at the opposite side thereof, to permit swinging movement of the spike therein to a limited extent, at each side of a position in which it extends in the direction of a radius of the rim.

The middle spike 7a is extended inward beyond the shaft in which it is mounted, and a

small coil spring 9 is attached to the inner end thereof and to the rim in position to hold all the spikes on the shaft in the full line position shown in Fig. 5.

5 The arrangement shown in detail in Fig. 6 is alternated with an arrangement indicated in Fig. 3 in which two spikes are extended thru holes in the rim similar to the holes 8 shown in Fig. 5 and are mounted in a shaft 6 in a manner similar to that already described, except that they are located midway between the middle of the rim and its edges, so that a staggered arrangement of the spikes will be provided on each wheel. That is, in the 10 arrangement shown, five circular rows of spikes are provided on each wheel, each spike being located opposite the middle of the spaces between the spikes in the adjacent rows.

20 A spring 9 is attached to a spike on each shaft, so that all the spikes will normally be held in the full line position of Fig. 5, in which position the sides of the holes 8 will act as stops to limit the swinging movement 25 by the springs. The angular position with relation to a radius, in which the spikes are held when in this position, is such that, when the wheels are propelled forwardly, so that they are rotated in the direction of the arrow in Fig. 4, the spikes on each shaft will be held perpendicularly to the surface of the ground when the ends thereof are brought into a position in which they are about to penetrate, so that, on further forward movement 30 of the wheel the spikes will be driven perpendicularly into the ground and will be drawn perpendicularly therefrom as indicated in Fig. 4, the springs yielding to permit the 35 spikes to swing away from their normal positions to the dotted line position of Fig. 5, and acting to return them to their normal positions when they are withdrawn. At the same time, if the spikes penetrate the ground to their fullest extent, the face of the wheels will 40 be pressed down on the ground about the spikes so that the surface will be rolled.

The axle 2 is extended beyond each side of the yoke 3 for a suitable distance and a pair of arms 10 are mounted on the extended portions thereof at each side of the yoke. A shaft 12 is mounted in the end portions of each pair of arms and a pair of wheels 14 are rotatably mounted on said shafts 12. An arm 15 is connected at one end to each shaft 45 12 and at its opposite end is securely bolted to the adjacent side of the yoke 3 in such a position that the arms 10 are held at a slightly obtuse angle to the yoke 3, or nearly at right angles thereto. Said arms 10 are of equal length and the arms 15 are connected to the yoke 3 in such positions that the shafts 12 are held in axial alignment, in which positions they are held adjacent the rims of the rolls or wheels 1, so that the greater portion 50 of the rim of each wheel 14 extends beyond

the ends of the spikes 7. However, for the purposes for which this construction is provided, the lengths of the arms 10 and the diameters of the wheels 14 may be varied, the principal essential being that the shafts 12 shall be held eccentrically of the axle 2 and that the diameter of the wheels 14 be such that a substantial portion of a segment of the rims thereof shall be extended beyond the ends of the spikes.

70 With this construction, when the device is to be used to perform its intended functions, the handle 4 will be held in a position similar to that of Fig. 1, in which the wheels 14 will be held above the axle 2 and out of contact 80 with the ground, and when the device is to be moved without having it perform its functions, the handle 4 will be swung over to the opposite position, so that the wheels 14 will first be brought into contact with the ground 85 and then on further movement of the handle in the same direction the rolls 2 will be lifted from the ground as shown in Fig. 2, so that the device will be wholly supported by the wheels 14, and may be readily moved without having the spikes touch the ground.

90 As all the wheels are freely rotatable on the axle 2 independently of each other, the direction in which the device is pushed may be readily changed without lifting it. Also, 95 by mounting the rolls on an axle, the diameter of which is substantially less than that of the holes in the hubs, relative vertical movement of the wheels is permitted in case a spike should strike a stone or hard spot which 100 might tend to break it.

I claim:

1. A turf roller comprising a wheel having a rim provided with a cylindrical rolling face, a series of shafts mounted for oscillation within said rim and extending in parallelism with the arcs and with the face thereof, a series of pointed spikes rigidly mounted in each shaft perpendicularly thereto, said spikes being extended through said rim beyond its face and arranged to swing with their respective shafts through limited arcs, and means for holding each shaft in a position in which the spikes thereof will simultaneously enter the supporting surface of the roller perpendicularly and will yield to permit withdrawal thereof in their entering positions.

110 2. A turf roller comprising a wheel having a rim provided with a cylindrical rolling face, a series of shafts mounted for oscillation within said rim and extending in parallelism with the axis and with the face thereof, and projecting beyond the edges of the rim at 115 each end, a series of pointed spikes rigidly mounted in the projecting end portions of each shaft and in an intermediate portion thereof and extending in perpendicular relation thereto, the intermediate spikes being extended through the rim and all of the spikes 120

being extended beyond said face and arranged to swing with their respective shafts through limited arms, and means for holding each shaft in a position in which the spikes 5 will simultaneously enter the supporting surface of the roller perpendicularly and will yield to permit withdrawal thereof in their entering positions.

In testimony whereof, I have signed my name to this specification.

JAMES FREDERICK BUEL.
